UNITED STATES PATENT OFFICE.

DUDLEY H. SCOTT, OF CLEVELAND, OHIO.

ELECTRICALLY-OPERATED APPARATUS FOR ICE-RINKS.

1,241,289.

Specification of Letters Patent. Patented Sept. 25, 1917.

Application filed March 24, 1917. Serial No. 157,289.

To all whom it may concern:

Be it known that I, DUDLEY H. SCOTT, citizen of the United States, residing at Cleveland, in the county of Cuyahoga and State of Ohio, have invented certain new and useful Improvements in Electrically-Operated Apparatus for Ice-Rinks, of which the following is a specification.

This invention pertains to electrically-operated apparatus for ice-rinks and means for transmitting electric current to such apparatus while under motion, and the invention is of especial utility in operating an electric tractor or motor driven ice planer over a circuitous and substantially spiral path on the skating floor of an ice rink.

In the preparation and maintenance of an ice floor in a skating rink the general practice is to employ an ice planer drawn by horses to cut down the ice body and smooth the ice surface, but my invention involves the use of an electrically-operated tractor and ice planer adapted to travel on the ice surface and cut the ice to the depth of an eighth of an inch, more or less, while the planer traverses a spiral path beginning at the rim or border of the ice field and working inward toward the center with an overlapping cut to eliminate all ridges in the area to be cut which usually exceeds one-half of an acre. The use of horses is objectionable from many standpoints, and the employment of a tractor deriving its power from an internal combustion engine is undesirable on account of the fumes discharged into the closed rink, while the use of electric storage batteries is too expensive and quite impracticable due to the large power and amount of current demanded. On the other hand, I find that this work may be accomplished more quickly and economically by electric power where the electric current is obtained from an established service station or power plant, and that the means for transmitting the electric current to the spirally-traveling planer or electric tractor must afford durable and safe electrical connections adapted to be coupled and uncoupled and also suspended for turning movement above the ice surface to facilitate operations of the planer. The working area of the ice planer being large, a relatively long and heavy electrical cable must be employed, part of which must trail over the ice behind the planer, and suitable provision must be made to support the

weight of this cable as well as to take care of its winding movement and tendency to knot occasioned by the spiral travel of the planer over the ice surface. To meet these exacting requirements I have provided power mechanism adapted to revolve the cable where suspended above the ice surface near the center of the ice field, and preferably at one side of the center to facilitate a straight travel of the planer on a median line of the rink during final cutting operations, and this mechanism is operable independently of the moving planer and under control of the operator directing the movement of the planer, all as hereinafter shown and described and more particularly pointed out in the claims.

In the accompanying drawings, Figure 1 is a transverse section of an ice skating rink showing a tractor and ice-planer on the ice floor and an electrical cable connected with the tractor and suspended from operating mechanism seated upon an arched girder which supports the roof of the building. Fig. 2 is a diagram view, in plan, of an ice-skating floor with an ice-planer and tractor and its electrical cable shown in full and dotted lines in several different positions thereon. Fig. 3 is a side elevation, partly in section, of the revoluble device for distributing the electric current and rotating and supporting the electrical cable and conduit, and Fig. 4 is a transverse section thereof on line 4-4, Fig. 3. Fig. 5 is a side view of the separable coupling for the divisional portions of the electrical cable and its conduit. Fig. 6 is a perspective view showing a portion of the frame of the planer or tractor, the terminal coupling members for the cable and its conduit, and a diagram of the electrical circuits for the operating and controlling parts carried by the planer or tractor.

The invention involves the use of a building 2 in which a solid ice floor 3 is maintained by circulating a refrigerating medium through pipes 4, and this ice floor is of rectangular or oval form preferably and of large area necessarily where a great number of skaters are to be accommodated. My practice is to create a new ice surface after each skating session by planing, flooding and freezing operations, and planing is accomplished in the present case by a knife planer 5 drawn over the surface by an electrically-operated tractor 6 deriving its electric current through insulated wires 7 con-

- ined within a flexible conduit 8 which is detachably coupled at one end to the tractor and at its other end to a tubular shaft 9 carrying a series of current collecting rings 10, and which shaft is rotatably supported in a suitable housing 11 located at a relatively high elevation above the center of the ice floor and preferably at one side of the longitudinal median line thereof. As shown, 10 housing 11 is mounted on roof girder 12 of building 2 adjacent an electric motor 13 which is belted in driving relation with a pulley 14 on a horizontal shaft 15 having a worm engaged with a large gear 16 on tubular shaft 9, see Fig. 3. Fixed rods 17 in housing 11 support a series of contact brushes 18 opposite the collector rings 10, and in the present instance five such rings are mounted in insulated position one above 15 the other upon shaft 9, each having a terminal connector 19 for a separate wire 7. Three wires 20 to the line connect with the three lower brushes 18, and three wires 21 connect motor 13 with the two upper brushes 25 and one of the lower brushes, thereby placing the electric motor 22 for the tractor and motor 13 for shaft 9 in the same line circuit with separate switches 23 and 24 on the tractor. In this way the operator of the 30 tractor controls not only the movement of the tractor and the planer over the ice, but also independent rotation of shaft 9 far above, thereby enabling him to rotate the suspended conduit and wires to correspond 35 to the circular and spiral movements and variable speed of the tractor and planer throughout planing operations. The conduit 8 comprises two separable sections of rubber or fabricated tube adapted to protect the wires from wear in trailing over the ice and from the twisting strains of rotation, and the section which depends directly from the shaft 9 has a tubular cross piece 25 with perforated extensions removably 40 pinned to forked arms of a tubular coupling member 26 which is secured to one end of the trailing section of tube or conduit 8. The wires 7 are also made in separate sections joined together by separable electrical 45 attachment plugs 27 and 28, plug 27 being located centrally between the forked arms of coupling member 26, and plug 28 being placed between the forked telescopic pipe. coupling 29 which is used to anchor the 50 trailing section of the tube or conduit 8 to a corresponding coupling member 30 fixed upon the chassis or frame of tractor 6. The forked coupling 29 projects at one side of the tractor to keep the trailing portion of conduit 8 clear of the tractor and planer, and the tube or conduit is wound with wire 55 to relieve the tube and electric wires of the twisting and pulling strains and the wear of contact with the ice.
- Following planing operations the tractor 65 and planer are removed from the ice, and the conduit and electric wires therein are uncoupled at the tractor and also where joined by coupling 26 and plug 27 seven to eight feet above the ice. Switch 23 which is mounted on the tractor is used to place the driving motor 22 for the tractor in the electric circuit, and switch 24 is used to start, stop and reverse motor 13 which operates shaft 9 of the rotary electric-current distributor in housing 11.
- What I claim is:
1. In electrically-operated apparatus adapted for use in a skating rink, an electric-current distributing device and an electrical cable in rotatable connection therewith, in combination with an electrically-propelled apparatus having an electrical coupling for said cable.
  2. Means for transmitting electric current to an electric tractor or planer traversing a circuitous path in an ice skating rink, comprising a revoluble electric-current distributor mounted in an elevated position within the rink and having an electrical cable suspended therefrom which is provided with an electrical coupling adapted to be connected with said electric tractor or planer.
  3. Means for transmitting electric current to an electric tractor or planer while under motion in an ice rink, comprising a revoluble electric-current distributing device, an electrical cable connected with said device and the electric tractor or planer, and controllable means to revolve said device.
  4. An electrically-propelled vehicle adapted to travel in a circuit on the floor of a skating rink, in combination with means for transmitting electric current to said vehicle while under motion, comprising an elevated rotary electric-current distributor having a flexible electrical cable suspended therefrom and rotated thereby and coupled to said vehicle.
  5. An electrically-propelled apparatus, in combination with a revoluble electric-current distributing appliance having a flexible conduit suspended therefrom, and electrical wires within said conduit in coupling connection with said apparatus and with said revoluble appliance.
  6. In combination, an electrically-propelled vehicle adapted for use in a skating rink, an electric-current supply cable connected with said vehicle and having an elevated rotatable support provided with electric-current collecting members, power means to rotate said support, and a controlling device to start and stop said power means.
  7. In an ice rink, an elevated support above the floor of said rink, a revoluble electric-current distributor mounted upon said support, an electrical cable and a flexible conduit therefor suspended from said revol-

- luble distributor, and separate coupling and attachment members at the lower ends of said conduit and cable, respectively, adapted to establish mechanical and electrical connections with transportable electrical apparatus in said rink.
8. A vehicle having electrical propelling mechanism and a trailing electrical connection therefor, in combination with a revoluble electric-current-distributing appliance having coupled union with said connections, and means to revolve said appliance and connection upon a circuitous travel of said vehicle.
9. Means for transmitting electric current to an electric vehicle in a skating rink, comprising a revoluble electric-current distributor having an electrical cable and a protecting tube for said cable suspended therefrom, said tube and cable being made in separable sections, each having a terminal coupling member to unite the sections.
10. An electrically-propelled apparatus having a coupling member projected at one side thereof, and a flexible tube affixed at one end in trailing connection with said member and having electrical wires extending therethrough, in combination with a rotatable support for the other end of said
- tube having electric current distributing connections for said wires.
11. In an ice rink, an electric-current distributor having a rotatable member mounted substantially centrally in an elevated position above the floor of the rink, electrical wires and a flexible conduit therefor suspended from said member and rotatable therewith, and separate coupling devices for the ends of said wires and conduit respectively, in combination with an electrically-propelled apparatus adapted to travel over the ice rink floor having coupling connection with said coupling devices.
12. In combination, an elevated rotatable electric-current distributing device and an electric motor in operable connection therewith, an electric cable for the transmission of electric current suspended from said device and rotatable therewith, an electrically-propelled apparatus in electrical connection with said cable, and means mounted upon said apparatus adapted to control the operation of said motor and electric-current distributing device.

Signed at Cleveland, in the county of Cuyahoga, and State of Ohio, this 23rd day of March, 1917.

DUDLEY H. SCOTT.
